Primary Examiner — Sheryl Lane*Assistant Examiner* — Mark T. Philipp(74) *Attorney, Agent, or Firm* — Cowan, Liebowitz & Latman, P.C.; Anastasia Zhadina(57) **CLAIM**

The ornamental design for engine cover, as shown and described.

DESCRIPTION

FIG. 1 is a front perspective view of engine cover showing our design;

FIG. 2 is a top plan view thereof;

FIG. 3 is a bottom plan view thereof;

FIG. 4 is a right-side view thereof;

FIG. 5 is a left-side view thereof;

FIG. 6 is a front view thereof; and,

FIG. 7 is a rear view thereof.

Broken lines showing portions of the engine cover are included for the purpose of illustrating environment and form no part of the claimed design.
